United States Patent Office

Des. 218,688
Patented Sept. 15, 1970

218,688

VIDEOTELEPHONE TRANSCEIVER CONTROL UNIT

Henry Dreyfuss, South Pasadena, Calif., and Rembert R. Stokes, Middleton, N.J., assignors to Bell Telephone Laboratories, Incorporated, Murray Hill, N.J., a corporation of New York

Original design application Nov. 24, 1967, Ser. No. 9,549,
now Patent No. 215,159, dated Sept. 9, 1969. Divided
and this application Oct. 3, 1968, Ser. No. 15,937

Term of patent 14 years

Int. Cl. D14—03

U.S. Cl. D26—14

FIG. 1

FIG. 2

FIG. 3

FIG. 1 is a left front perspective view of a videotelephone transceiver control unit showing our new design; FIG. 2 is a side perspective view of the videotelephone transceiver control unit shown in FIG. 1; and

FIG. 3 is a rear view of the video telephone control unit shown in FIG. 1.

This is a division of design application Ser. No. 9,549 filed Nov. 24, 1967 and now Pat. No. D-215,159.

We claim:

The design for a videotelephone transceiver control unit, substantially as shown and described.
